UNITED STATES PATENT OFFICE.

JAMES M. SANDERS, OF NEVIN, OHIO.

DESIGN FOR A THINNING-TOOL FOR COTTON, &c.

SPECIFICATION forming part of Design No. 26,333, dated November 24, 1896.

Application filed October 6, 1896. Serial No. 608,062. Term of patent 14 years.

To all whom it may concern:

Be it known that I, JAMES M. SANDERS, a citizen of the United States, residing at Nevin, in the county of Highland and State of Ohio, 5 have invented a new and original Design for Corn and Cotton Thinning Devices, of which the following is a specification.

This invention relates to a new and original design for a corn and cotton thinning device, and it has for its object to provide a design of this character that shall be both useful and ornamental.

The leading feature of the design resides in an elongated cylindrical handle, and a 15 squared straight shank-piece extended on a straight line from one end of the handle and having a flat blade portion extended in a right-angular direction from the shank-piece and having its flat surfaces disposed at an 20 obtuse angle to said shank-piece, said blade portion being formed on the arc of a circle with its edges approximately parallel as they approach the shank-piece.

A minor feature of the invention is the convergence of the edges of the blade portion toward the tip thereof to form a V-shaped point, and having the blade portion of an inwardly-tapering thickness.

In the drawings, Figure 1 is a perspective 30 view of a corn and cotton thinning device

embodying the herein-described design. Fig. 2 is a plan view thereof. Fig. 3 is an elevation of the same.

Referring to the drawings, the numeral 1 designates an elongated cylindrical handle 35 having extended on a straight line from one end thereof the squared straight shank-piece 2. The straight shank-piece 2 is formed with a flat blade portion 3, extended in a right-angular direction from the shank-piece and having its flat surfaces disposed at an obtuse angle thereto. The blade portion 3 is formed on the arc of a circle with its edges 4 approximately parallel as they approach the shank-piece, and which edges converge toward the tip of the blade portion to form a 40 V-shaped point 5. The blade portion 3 of the device is beveled, so as to be formed with an inwardly-tapering thickness.

What I claim is—

The design for a corn and cotton thinning device herein shown and described.

In testimony that I claim the foregoing as my own I have hereto affixed my signature in the presence of two witnesses.

JAMES M. SANDERS.
